UNITED STATES PATENT OFFICE.

ARNOLD GEORGE PETERS, OF MINNEAPOLIS, MINNESOTA.

DESIGN FOR A LAMP-CASE.

48,393.

Specification for Design.

Patented Jan. 4, 1916.

Application filed October 1, 1915. Serial No. 53,641. Term of patent 14 years.

To all whom it may concern:

Be it known that I, ARNOLD GEORGE PETERS, a citizen of the United States, residing at Minneapolis, in the county of Hennepin and State of Minnesota, have invented a new, original, and ornamental Design for a Lamp-Case, as shown in the accompanying drawings, whereof the following is a description.

Fig. 2 a rear elevation, and Fig. 3 an end elevation.

I claim:

The ornamental design for lamp case as shown and described.

ARNOLD GEORGE PETERS.

Witnesses:

ROBERT H. TUTTLE,

ROY C. THOMPSON.
